(57) **CLAIM**

The ornamental design for a resistance band, as shown and described.

DESCRIPTION

FIG. 1 is a perspective view of an resistance band, illustrated in use;

FIG. 2 is a front perspective view of the resistance band;

FIG. 3 is a front elevation view of the resistance band;

FIG. 4 is a rear elevation view of the resistance band; FIG. 5 is a left side elevation view of the resistance band; the right side elevation view being a mirror image thereof; and, FIG. 6 is a top plan view of the resistance band; the bottom plan view being a mirror image thereof.

The broken lines shown in the drawings illustrate environment and portions of the resistance band that form no part of the claimed design.

1 Claim, 4 Drawing Sheets(56)
